UNITED STATES PATENT OFFICE.

GASTON J. LIPSCOMB, OF NEW YORK, N. Y.

GAZZING HOOD.

Application filed May 18, 1923. Serial No. 639,831.

To all whom it may concern:

Be it known that I, GASTON J. LIPSCOMB, a citizen of the United States, residing at New York, in the county of New York and State of New York, have invented certain new and useful Improvements in Gassing Hoods; and I do hereby declare the following to be a full, clear, and exact description of the same, reference being had to the accompanying drawings, forming part of this specification.

This invention relates to gassing hoods in general and particularly to that class of hoods designed primarily for the gassing of boll-weevils.

The principal object of the present invention is to provide a simple and efficient gassing hood for covering a plurality of plants while subjecting them to the action of a lethal gas. Other and further objects of the invention consist generally in the details of construction of the hood and are particularly pointed out in the claims.

The devastation due to the boll-weevils is well known and many different types of apparatus have been designed for use with various poisonous gases for applying the poison in a convenient and orderly manner to the growing cotton plants. A number of such devices are limited rather sharply to the particular kind of poison used, some employing lethal gas and others using a liquid spray of insecticide. In the present hood any desired poisonous gas may be employed limited only by the requirement that the gas shall not be harmful to the growing plants although fatal to the insects.

A very convenient and important, although not absolutely essential, feature of the invention is the provision of a plurality of spring hinged bristle doors serving to knock or jar the weevils from the squares in order that they may fall into the pockets provided in the hood and thereby subjecting them to a stronger concentration of the gas provided such gas is heavier than air. While I do not wish my invention to be limited in any way to use with a particular gas I find that the most convenient and efficient gas for exterminating these pests is that which is produced by heating together crude petroleum and sulphur in a closed retort using approximately fifteen parts of the oil to thirty-two parts of the sulphur. The gas thus produced may be liquefied and is very effective in quantities as small as

one-tenth of one per cent, although I prefer to use this gas, which is carried by the gassing hood in a liquid form, in somewhat stronger quantity, usually in the neighborhood of one-half of one per cent, that is, one part of gas by volume to two hundred parts of atmospheric air.

In the drawings illustrating a preferred type of my gassing hood,

Figure 1 is a top plan view with a portion of the canvas covering removed in order to show more clearly the structure of the framework.

Fig. 2 is a side elevation partly in central vertical section.

Fig. 3 is a vertical section on line 3—3 of Fig. 1.

Fig. 4 is a section on line 4—4 of Fig. 1.

Fig. 5 is an end view of the device.

Fig. 6 is a view similar to Fig. 4 but on a much larger scale.

Fig. 7 is a side view of the ground wheels and the fan structure.

Fig. 8 is a section on line 8—8 of Fig. 6.

Figs. 9, 10 and 11 are detail views showing the supporting structure for the fans and the driving mechanism of the fans.

The hood consists generally in a covered structural steel frame supported by a pair of ground wheels 10 and driven or pulled in any desired manner, the connection for pulling or pushing being purposely omitted in order not to restrict the invention in any way. The hood may obviously be horse-drawn or may be towed from a vehicle of any nature, or may be pushed by hand.

The framework in the preferred form illustrated in the several figures includes a plurality of arches each consisting of a piece of channel iron irregularly bent into the form best seen in Fig. 6. At each side of the central portion 11 which forms the top the channel is bent downwardly to form the sloping portions 12 of the roof of the hood and the channel is then bent through a sharp angle, almost 90°, to form the long side pieces 14 of the framework and finally the ends 15 are bent upwardly to an acute angle with the side members 14, the two end pieces 15 being directed toward each other and slightly upward.

The several outer arches thus formed are connected together by a plurality of longitudinal rolled iron sections such as the members 18 between the flat and sloping sections of the roof; the angle irons 19 at

the junction of the roof and side sections, and the angle members 20 at the junction of the side pieces 14 and end pieces 15. These various angle pieces extend the entire 5 length of the gassing hood and with the crossed tie members 22 of the sides and the several struts 23 of the roof section form the outer framework supporting the canvas covering 24 which encloses the hood on the 10 top, sides, and bottom, it being noted that the canvas covering 24 extends between the channel ends 15, the angles 20, and the angle irons 25 which connect the tips of the ends 15 of the various channel members forming 15 the outer arches of the framework.

A second series of arches is formed inside of the first mentioned arches, each of the members being formed from channel iron slightly less in size than the channel irons 20 forming the members 11, 12, 14 in order that the channel members of the outer and inner arches may nest together as best seen in Fig. 8. The inner arch includes two side members 30 which are bent inwardly at approximately 25 their centers to form converging side members 31 which are fastened at their lower ends to the longitudinal angle irons 25 and nest within the outer channel members at the vertex between the sections 30 and 31 30 where the outer channel members are connected together by the main angle pieces 32 which run the entire length of the hood and serve to support the frame work on the ground wheels 10 as well as on the auxiliary 35 wheels 33 which as shown are in the nature of casters.

Each of the two ground wheels 10 carries a grooved wheel 35 which drives a wheel 36 on the shaft 37 which also carries the somewhat larger grooved wheel 38, the latter driving, through the belt or chain 40 and the meshing gears 41 and 42, one or more fans 44. In order that the hood may be reversible I preferably provide a plurality of fans 45 44 at each side, each having the usual clutch (not illustrated) in order that one or the other of the fans may be in operation depending upon the direction of travel of the hood. The way in which these various elements are supported in the framework is 50 clearly shown in Figs. 9 to 11.

The frame of each end of the gassing hood is identical with the frame formed by each pair of the arches so that a description of 55 one will suffice for the remainder, the sole difference being that in each of the outer frames, as illustrated in Fig. 5, the space between the angle sections 12, 14 and 30 is enclosed in canvas as is the trapezoidal section 60 between the members 11, and the transverse rods 46 which extend between the side members 30 of the inner arch members, one of these members 46 being located at each arch.

At each one of these transverse frames in-

cluding the two ends I hinge a number of bristle doors adapted to strike the cotton plants so as to jar or shake the insects from the squares. Preferably there are five such doors to each transverse frame the upper 70 door 50 preferably swinging fabric flap being connected at its upper edge to the transverse member 46 and having a plurality of depending bristles 51 which just clear the upper edges of the doors 53 hinged to the side members 30 of the inner arch. The lower doors 54 are generally similar to the spring hinged doors 53 having horizontally disposed bristles 55 slightly overlapping in the center as shown, the principal difference 75 being that the doors 54 carry at the bottom edge a number of radially disposed bristles to fill in the space to the bristles 56 carried by each of the longitudinal angle irons 25 joining together the tip ends of the channels 80 forming the inner and outer arches of the sections.

It will be noted from the various figures, particularly Fig. 5, that each end of the hood is entirely closed so that the hood forms a nearly gas-tight chamber. On referring to Figs. 3, 4, and 6, however, it will be noted that the space triangular at each side of each section, between the members 12, 14 and 30 is entirely open longitudinally 90 so that a duct is formed from one end of the hood to the other. The various members 30 of the inner arch are covered with canvas 60 throughout the extent of the hood except for each end section at which place the canvas 60 is omitted. That is, the canvas extends from the next to the end member 30 at one end of the hood to the next to the end member 30 at the opposite end of the hood so that at each end of the hood there is a chamber which extends from side member 14 to side member 14, in other words, the central chamber is in communication 95 with the side ducts at each end of the device.

The purpose of this construction is to 100 provide a continuous circulation of the poisonous gases through the hood. The fans 44, preferably located at the center of the device as best seen in Fig. 2, provide a circulation of the gases in one direction through the two ducts formed between the members 30 and 14 and as a consequence of the formation of this current of air and gas the mixture passes in opposite directions 105 through the center of the hood in contact with the plants.

In the metallic cylinder or gas container 110 62 located on top of the hood I store a quantity of the gas formed by heating together crude oil and commercial sulphur which gas is found to be an exceptionally good insecticide as it leaves a very fine deposit of sulphur upon the growing plants. The steel cylinder 62 is equipped with a 115 standard stop valve 64 and a reducing valve 120 125 130

65 of the usual type in addition to the two stop valves 66 which control the outlet of gas from the steel cylinder through the pipe 67 to the central chamber of the hood. The 5 gas is preferably liquefied and is consequently under pressure.

In operation the hood is placed in such a manner as to straddle a row of cotton plants which extend between the bristles 56 at the 10 bottom of the hood and into the chamber formed by the canvas covering 24 over the members 15 and 14 at the bottom and the canvas 60 over the members 30 at the upper sides and again by the canvas 24 extending 15 over the central sections of both of the two channel members at each joint of the frame. As the gassing hood is drawn along, preferably in continuous fashion, the growing cotton plants enter successively the forward 20 end of the hood, passing between the wide bristle doors 53 and 54 and if the plants are of sufficient height also pressing aside the doors 50.

The valve 66 near the forward end of the 25 hood, which of course depends solely on the direction of the travel of the device since the hood is entirely reversible, is open to such an extent as to provide the proper strength of the gas, namely, approximately 30 one-half of one per cent of the gas. By reason of the travel of the hood the gas will be moved to the rear end of the hood but its direction of travel will be reversed and its circulation greatly aided and augmented by 35 the two forwardly directed fans 44 in operation (the rearwardly directed fans having been rendered inoperative) which direct the gaseous mixture in the two return ducts 68 toward the front of the vehicle, from whence 40 it passes rearwardly through the hood to the rear ends of the ducts 68, thus providing a continuous circulation of the poisonous gases and preventing excessive loss of the gas through the rear doors which while not 45 gas-tight are substantially so, the valve 66 admitting only sufficient quantity of gas from the steel cylinder to make up for the loss at the bottom and rear.

It will be obvious that the amount of 50 gas used will depend entirely upon the speed of travel of the hood, the size of the gas chamber used and the gas tightness of the rear end of the hood and of the lower bristles 56. With a suitable mixture 55 of air and poisonous gas such as described the boll-weevil is almost instantly paralyzed and the sharp jarring movement given to the plants by the bristle doors at each of the several sections as the plant passes through the hood causes the partially 60 or fully paralyzed weevil to be knocked from the squares and plant and to fall into the ledge between the longitudinal angle irons 20 and 25 which forms a pocket at 65 either side of the bottom bristle brushes

56. The weevils either dead or paralyzed fall into these collecting pockets at the two bottom corners of the device, these ledges or pockets extending the entire length of the hood. Since the gas used is somewhat 70 heavier than air the atmosphere in these lower corner pockets has a somewhat higher concentration of the gas and hence even with a very weak mixture any paralyzed weevils accumulating in these pockets will 75 be killed within a very short space of time.

What I claim is:

1. In a device of the character described, a skeleton frame, a covering for the top and sides of said frame, a flexible closure 80 for the bottom of said frame, and a plurality of longitudinal partitions dividing the interior of the device into a plurality of chambers.

2. In a device of the character described, 85 a skeleton frame, a covering for the top and sides of said frame, a flexible closure for the bottom of said frame, and a plurality of longitudinal partitions dividing the interior of the device into a plurality 90 of separated chambers.

3. In a device of the character described, a skeleton frame, a covering for the top and sides of said frame, a flexible closure for the bottom of said frame and a plurality 95 of longitudinal partitions dividing the interior of the device into a main chamber and two return passage ducts.

4. In a device of the character described, a skeleton frame, a fabric covering for the 100 top and sides of said frame, a plurality of longitudinal partitions dividing the interior of the device into a main chamber and a plurality of separated return ducts, a gas reservoir delivering poisonous gas within 105 said device, and a fan in each duct for causing a circulation of gas and air through said main chamber.

5. In a device of the character described, a skeleton frame, a fabric covering for the 110 top and sides of said frame, a plurality of ground wheels supporting said frame at the center, a flexible closure for each end of said device, a flexible closure for the bottom of said device, means for delivering a poisonous gas to the interior of said device, and means for circulating the gas and air mixture.

6. In a boll weevil gassing hood, a frame having a central chamber through which the plants are passed and side chambers partitioned from said central chamber, supporting ground wheels for the frame, means for delivering a poisonous gas to the side chambers, and a ledge at the bottom of 125 each side chamber for collecting the weevils and holding them in the atmosphere of poisonous gas.

7. A plant treating machine comprising a mobile hood adapted to be moved over 130

vegetation, positive means for forcing gas in contact with vegetation beneath the hood and means for withdrawing the gas from beneath the hood for reuse.

8. A plant treating machine comprising a mobile hood adapted to be moved over vegetation, means for forcing gas into contact with vegetation beneath the hood, and positive means for withdrawing the surface plus gas from beneath said hood for reuse.

9. A plant treating machine comprising a mobile hood having an inlet adjacent its front end, means for forcing gas through said inlet into intimate contact with vegetation beneath the hood, an outlet adjacent the rear end of said hood and means for positively withdrawing gas through said outlet to be used over again. 15

GASTON J. LIPSCOMB.
